(57) **CLAIM**

The ornamental design for a device for holding bait tubes, as shown and described.

DESCRIPTION

FIG. 1 is a front elevational view of a device for holding bait tubes, in accordance with a first embodiment of my new design;

FIG. 2 is a side elevational view of the device for holding bait tubes of FIG. 1, taken from the left side of FIG. 1;

FIG. 3 is a side elevational view of the device for holding bait tubes of FIG. 1, taken from the right side of FIG. 1;

FIG. 4 is a rear elevational view of the device for holding bait tubes of FIG. 1;

FIG. 5 is a top plan view of the device for holding bait tubes of FIG. 1;

FIG. 6 is a bottom plan view of the device for holding bait tubes of FIG. 1;

FIG. 7 is a perspective view of the device for holding bait tubes of FIG. 1, showing the device holding two bait tubes, the bait tubes forming no part of the design;

FIG. 8 is a front elevational view of a device for holding bait tubes, in accordance with a second embodiment of my new design;

FIG. 9 is a side elevational view of the device for holding bait tubes of FIG. 8, taken from the left side of FIG. 8;

FIG. 10 is a side elevational view of the device for holding bait tubes of FIG. 8, taken from the right side of FIG. 8;

FIG. 11 is a rear elevational view of the device for holding bait tubes of FIG. 8;

FIG. 12 is a top plan view of the device for holding bait tubes of FIG. 8;

FIG. 13 is a bottom plan view of the device for holding bait tubes of FIG. 8; and,

FIG. 14 is a perspective view of the device for holding bait tubes of FIG. 8, showing the device holding a bait tube, the bait tube forming no part of the design.
